UNITED STATES PATENT OFFICE.

EDWARD L. ALLEN, OF PITTSBURGH, PENNSYLVANIA.

GARMENT-SUPPORTER.

1,312,718.

Specification of Letters Patent.

Patented Aug. 12, 1919.

Application filed October 3, 1917. Serial No. 194,518.

To all whom it may concern:

Be it known that I, EDWARD L. ALLEN, a citizen of the United States, residing at Pittsburgh, in the county of Allegheny and 5 State of Pennsylvania, have invented new and useful Improvements in Garment-Supporters, of which the following is a specification.

This invention relates to garment supporters, and particularly to garment supporters of that type having a spring clasp 10 to engage the fabric of a garment.

One object of the invention is to provide a novel construction of spring wire clasp 15 whereby simplicity and increased efficiency of gripping action are obtained.

Another object is to provide a supporter embodying clasps or gripping members to engage garment members and an elastic connection 20 between the same, whereby provision is made for efficiently supporting one garment member from the other.

Still another object is to provide a supporter which, by variations of construction 25 in the elastic connection, is adapted for various uses.

The invention consists of the features of construction, combination and arrangement of parts, hereinafter fully described and 30 claimed, reference being had to the accompanying drawing, in which:—

Figure 1 is a view of the clasp *per se*.

Figs. 2, 3 and 4 are views showing the use 35 of the clasp in different forms of supporters.

In carrying my invention into practice, I provide a clasp 1 made from a single piece or length of spring wire. This clasp 1 is bent at one end to form a triangular loop 2. From one of the sides or arms of the loop 40 projects a straight shank 3, integral with said arm or side of the loop and the lower portion of which forms a spring jaw 4. The shank body 3 and jaw 4 are arranged in horizontal alinement with each other, the 45 jaw forming a straight continuation of the straight shank, and said shank and jaw extend from the apex of the triangular loop and are arranged in line with the major axis of said loop. The opposite end of the wire 50 is bent to form a spring jaw 5 which is parallel with the jaw 4 and coextensive in length therewith. This jaw 5 terminates at its upper end in transverse alinement with the imaginary line of division between the 55 jaw 4 and shank 3 and is integrally con-

nected at its lower end with the jaw 4 by a bent or return portion 6. The upper end of the jaw 5 terminates in a lateral extension 7, forming a combined finger piece and bearing member, which extension 7 is completed by the terminal portion 8 of the wire, which is bent or folded thereunder forming a doubled projection, the portions of which lie in the same plane, thus increasing the area of the combined finger and bearing member, as well as the strength thereof, and disposing the free end of the wire in such a manner as to prevent it from hooking into or otherwise injuring the garment or the hand of the user. The jaws 4 and 5 may be slightly spaced apart, and the jaw 5 is movable relatively to the jaw 4 to admit a portion of the garment between said jaws, whereby such portion of the garment may be held and clamped. The extension 7 may be disposed at an obtuse angle to the jaws to form a flaring entrance space for the free insertion and removal of the portion of the garment to be held, while at the same time allowing said extension to project laterally to a sufficient degree to form an easily grasped finger piece and a bearing member of adequate bearing area. The spring wire clasp as thus constructed has all its portions disposed in the same plane, thus forming a clasp which is adapted to lie flat 80 against the person of the wearer and is void of projections liable to tear or otherwise injure the clothes or person of the wearer.

In Fig. 2 I have illustrated one mode of use of the improved clasp, in which it is shown as employed in duplicate for the production of a garter, sleeve holder or shirt holder. As shown, two of the clasps are employed, which project in opposite directions, or with their triangular loops 2 facing each other, the said clasps being connected by a flat strip 9 of elastic webbing having its end portions passed through the loops and stitched or otherwise secured to the body of the web. The device as thus constructed may be used as a garter for directly connecting the hose with an under garment, the upper and lower clasps being engaged with portions of the hose and under garment as shown. By this construction the hose will be supported from downward movement and the under garment from upward movement, and the elastic strip will hold the parts in proper position, while permitting 100 105 110

the device as a whole to expand and contract to accommodate the body movements of the wearer. This construction of device may also be employed as a sleeve holder, 5 above and below a certain point, for the purpose of holding the lower end or cuff of the sleeve elevated or for taking up a portion of a sleeve of abnormal length. The device may also be used for connecting the 10 lower portion of a shirt with an under garment for holding the shirt down and preventing it from creeping up, in the event of the use of a belt instead of suspenders as a trousers' support.

15 In Fig. 3 I have shown another mode of use of the clasp for a different type of hose supporter, in which a single clasp is employed at the top of the supporter for engagement with the under garment and a 20 pair of diverging clasps are employed at the lower end of the supporter for engagement with the hose. In this structure the upper clasp is connected by an elastic strip 10 with an elastic loop 11 connected in turn 25 by other elastic strips 12 with the lower clasps, by which construction the parts of the clasp are limited to a relative longitudinal movement and maintained in proper position by the web 10, and the lower clasps 30 are permitted to assume an angular position and maintained in such position and limited in lateral movement by the elastic loop 11 and elastic strips 12. This construction of the supporter effectually operates to prevent 35 turning or lateral movement of the hose engaging clasps and secures the hose against any possibility of accidental disengagement or displacement, while allowing free motions of the limb of the user in all directions.

40 In Fig. 4 I have shown the device adapted for use as a supporter and fastener, for connecting the hose with knee-length under garments and holding the hose and garment in proper position. In this structure the 45 upper clasp 1 is connected by a short elastic web 13 with an upper elastic loop 14, which is connected by a long elastic strip 15 with a lower elastic loop 16, with which a pair of lower clasps 1 are connected in the same 50 manner as shown in Fig. 3. The strip 15 is of proper length to adapt the device to extend between the under garment and hose, and has one of its ends passed through the loop 14 and folded over upon itself and 55 stitched or otherwise secured, and has its other end passed through the loop 16 and secured to a slide 17 adjustably engaging the body of the elastic strip, whereby the

length of the strip may be varied as circumstances require.

60 In the various applications to which the clasp may be put, it will be observed that by reason of the fact that the clasp is made of a single piece of spring wire, all of whose portions lie in a single plane, a firm bearing 65 of the clasp against the person of the wearer will be secured and a reliable and efficient clamping action upon the garment obtained. Also it will be seen that the lateral extension 70 will serve as a finger piece allowing the 70 clasp to be easily engaged with and disengaged from the garment, and with its extremity 8 will form a bearing member to rest squarely against the body of the wearer and prevent the clasp as a whole from turning or twisting laterally, the advantages of 75 which will be apparent.

Having thus fully described my invention, I claim:

1. A clasp for garment supporters comprising a length of spring wire bent at one end to form a triangular loop, the body portion of said wire extending straight from the vertex of the loop and perpendicular to the base thereof, the opposite end of the 85 said wire bent back upon itself to form a pair of parallel jaws spaced slightly apart and in substantial alignment with the loop vertex, and the free end of the backwardly bent portion extended laterally at an angle 90 to the jaws.

2. A clasp for garment supporters formed from a single piece or length of spring wire, the said wire being bent at one end to provide a triangular loop, thence extended from one of the side arms of the loop at the apex thereof to form a straight shank and a spring jaw continuous therewith, said shank and jaw being disposed in longitudinal alignment with each other and with the 95 major axis of the triangular loop, the wire thence being bent backwardly upon one side of and parallel with the spring jaw to form a second spring jaw, both of said jaws extending parallel to the direction of the 100 strain thereon, an extension continuous with said second jaw bent at an obtuse angle 105 thereto at a point medially between the apex of said loop and the backwardly bent portion of said wire, and a terminal portion 110 doubled beneath said extension, all of said portions of the wire clasp being arranged to lie in the same plane.

In testimony whereof I affix my signature.

EDWARD L. ALLEN.
